Eaton Corporation Brochure—Lifesense Hydraulic Hose Condition Monitoring 3 pages. Document No. E-HOOV-MR011-E, Printed in USA, March 2011.

Primary Examiner — John Windmuller*Assistant Examiner* — Steven Czyz(74) *Attorney, Agent, or Firm* — Jarett D. Millar(57) **CLAIM**

The ornamental design for a sensor enclosure assembly for a hose, as shown and described.

DESCRIPTION

FIG. 1 is top perspective view of a second embodiment of a sensor enclosure assembly for a hose.

FIG. 2 is a bottom perspective view of the sensor enclosure assembly for a hose of FIG. 1.

FIG. 3 is a left elevation view of the sensor enclosure assembly for a hose of FIG. 1.

FIG. 4 is a right elevation view of the sensor enclosure assembly for a hose of FIG. 1.

FIG. 5 is a top plan view of the sensor enclosure assembly for a hose of FIG. 1.

FIG. 6 is a bottom plan view of the sensor enclosure assembly for a hose of FIG. 1.

FIG. 7 is a front elevation view of the sensor enclosure assembly for a hose of FIG. 1; and,

FIG. 8 is a back elevation view of the sensor enclosure assembly for a hose of FIG. 1.

The broken lines illustrate portions of the sensor enclosure assembly for a hose which form no part of the claimed design.

1 Claim, 3 Drawing Sheets---
